DRILL PIPE PROTECTOR

Walter G. L. Smith, Los Angeles, Calif., assignor to Thermoil Company, Trenton, N. J., a corporation of Delaware

Application May 19, 1941, Serial No. 394,145

6 Claims.

(Cl. 308—4)

This invention relates to drill pipe protectors for use on sections of a string of well drilling pipe to protect the pipe from wear against the well casing or the side walls of the well in the operation of a rotary well drilling rig.

It has been customary to make the drill pipe protectors in the form of rings of rubber or other resilient material and to secure them upon the pipe in positions fixed both longitudinally and circumferentially of the pipe. It is of obvious advantage to prevent movement of the drill pipe protector longitudinally of the pipe as otherwise the protector under the action of gravity will move downward to the nearest coupling. The disadvantage of a circumferentially fixed mounting of the protector upon the drill pipe has been recognized. The drill pipe in rotary drilling is slowly rotated on its axis. A protector circumferentially fixed upon it, when thrown by the pipe against the sides of the well, is subject to a glancing blow which is obviously more destructive of the protector than is a blow delivered perpendicularly to the protector with no tangential component. Even when the drill pipe is not rotated, if it swings outwardly throwing the protector against the sides of the well, it is apparent that either because of irregularities in the surface of the side walls of the well or because the protector may be thrown at an angle against the side walls, the force of the impact will have a destructive tangential component.

The tangential component of a blow against the protector will be less destructive if the protector is free to rotate upon the pipe. Part of the force of impact may then be used to spin the protector upon the pipe instead of having to be absorbed by the resilient material of the protector. However, the problem of mounting a protector rotatably upon the drill pipe presents two major difficulties. The bearing between the rotatable protector and the pipe affords lodgment for the mud fluid used in the drilling operation and this mud fluid cuts through the drill pipe with extreme rapidity. The second difficulty lies in the provision of a means for preventing movement of such a rotatable drill pipe protector longitudinally of the pipe, which is practicable and will stand up under the severe conditions which obtain in a well during the well drilling operation.

A drill pipe protector of this invention has the advantages attendant upon a rotative resilient ring and has not the disadvantages of being the cause of a rapid cutting of the pipe radially be- 55

neath the ring and of having an ineffective short-lived longitudinal retaining means.

It is one object of the invention to provide a drill pipe protector which will stand up under the heavy blows to which it is subjected.

It is another object of the invention to provide in a practical form a rotatable resilient protector.

It is another object of the invention to provide a protector which will be both longitudinally stationary and circumferentially rotatable with respect to the pipe.

It is another object of the invention to provide in a rotatable drill pipe protector, a bearing for the rotating ring or spinner into which the mud fluid cannot enter to cut through the wall of the drill pipe.

It is another object of the invention to provide a drill pipe protector which is held stationary longitudinally of the pipe by means of a relatively stretchable resilient inner annular element shrunk on the pipe and which protector takes blows against the sides of the well by means of a relatively hard rubber ring carried by the inner annular element on the drill pipe.

It is another object of the invention to provide a convenient method for assembling in position upon the drill pipe a drill pipe protector comprising two members, an inner annular resilient body adapted to be shrunk on the pipe and an outer annular resilient body rotatively mounted in longitudinally fixed position upon the inner ring.

In the drawing, which is for illustrative purposes only:

Fig. 1 is a perspective view of a drill pipe protector embodying this invention shown in assembled position upon a section of drill pipe, the drill pipe being shown in fragmentary view;

Fig. 2 is a longitudinal section of the protector and pipe section shown in Fig. 1;

Fig. 3 is a longitudinal section of the base of the drill pipe protector;

Fig. 4 is an end view of the base;

Fig. 5 is a longitudinal sectional view of the rotatable ring or spinner of the drill pipe protector;

Fig. 6 is an end view of the spinner;

Fig. 7 is a longitudinal sectional view of the base of the drill pipe protector shown on a storage or handling mandrel;

Fig. 8 is a longitudinal sectional view of the spinner shown on a storage or handling mandrel;

Fig. 9 is a longitudinal sectional view of a mod-

ified form of the drill pipe protector of this invention;

Fig. 10 is a longitudinal sectional view of another modified form of a drill pipe protector of this invention; and

Fig. 11 is a longitudinal sectional view of still another modification of the invention.

A drill pipe protector of this invention generally designated by the numeral 11 comprises a base 12 and a spinner 13.

The base 12 is preferably a one-piece block of rubber or other like resilient material having a central bore 16 and a cylindrical outer face 15. An annular groove or slot 14 disposed centrally of the block extends inwardly from the outer cylindrical surface 15 of the block partway toward the bore surface 16. The annular slot 14 provides end flanges 17 and a central neck 18. Preferably the outer annular edges of the ends of the base are beveled to present annular end faces 19.

The rotatable ring or spinner 13 has the shape shown in Figs. 5 and 6. It has a bore surface 20, an outer cylindrical surface 21, and end faces 22, the outer edges of the end faces being preferably beveled to form faces 23. The length of the spinner 13 is slightly less than the length of the slot 14.

Both the base 12 and the spinner 13 are preferably manufactured in accordance with the invention which is the subject matter of an application for patent by Adelbert M. Graham, Serial No. 389,759, filed April 22, 1941. In accordance with the invention of that application, one-piece cylindrical rubber pipe protectors are made by spirally winding upon a mandrel a thin sheet of hot compounded uncured rubber taken directly from the final roll of a calender roll machine. The laminated cylinder thus formed is cured on the mandrel in a vulcanizing furnace and while still on the mandrel is turned down to the proper diameter and cut to the proper length. It is then removed from the mandrel and upon removal shrinks to a slightly smaller diameter both as to its bore and its outer cylindrical surface. The molecules of each lamina are in a condition to set up circumferential stresses tending to still further shrink the protector as to its diameter and the laminae are bonded to each other by an adhesive relationship resulting from the superimposing of the spiral convolutions while in a hot "tacky" condition.

In using the method of the invention disclosed in application Serial No. 389,759, the spinner is made without modification of the invention as therein disclosed. In making the base 12, the invention is modified by moving separator knives or blades up to the first calender roll against which the rubber stock is thrown after the base is built up to the diameter of the neck 18. These separator knives or blades are spaced from each other an interval equal to the length of the groove 14 and are placed at points along the calender roll corresponding to end walls 24 of the groove 14 (see Fig. 3). The rubber stock is then thrown against the calender roll between the separator blades and the end of the base to form the flanges 17.

The finely spaced lines 34 on the drawing indicate the bonding joints between laminae.

The base 12 is expanded by means of a machine such as is shown in the application of Adelbert M. Graham, Serial No. 346,615, filed July 20, 1940, and transferred to a storage or handling mandrel which may be for convenience termed a "holder," such as is also described in applica-

tion Serial No. 346,615 of Adelbert M. Graham. In Fig. 7 the base is shown thus mounted on a holder 25, the holder being formed of thin-walled pipe. By comparing the base as shown in Fig.

5 7 with the base as shown in Fig. 3, it will be observed that the inside and outside diameters of both the flanges and the neck have been greatly increased, the wall thickness and the length of the flanges have been decreased, and the neck 10 18, due to its thin wall, has buckled and shows one or more folds between the flanges.

The spinner 13 is similarly expanded and placed upon a holder 26 of a larger diameter than the holder 25. The base and spinner are now ready 15 for assembly upon a section of drill pipe.

During the drilling operation and after the kelly has been disconnected from the uppermost section of the drill pipe or when the pipe sections are on a pipe rack or otherwise disposed singly 20 or in double or treble stands, the holder 25 with the base 12 mounted thereon is telescoped over one end of the section of drill pipe together with hydraulic means assembled with the holder 25 such as is shown in the above mentioned application 25 Serial No. 346,615 of Adelbert M. Graham. The holder 25 has a bore of sufficient size to pass over any sleeve coupling or tool joint which may be secured to the drill pipe. A fragmentary view of a pipe section 27 is shown in Fig. 2 of the drawing. When the holder 25 and the hydraulic mechanism assembled thereon is at the point along the drill pipe at which it is desired to secure the drill pipe protector, the hydraulic means is operated to slide the holder 30 35 relative to the base 12, allowing the base to contract and closely grip the section of drill pipe 27. The holder 25 and its assembled hydraulic mechanism is then passed over the protector and removed from the end of the drill pipe section. 40 During this operation, since the holder 25 is in frictional engagement with the lower flange 17 after the upper flange 17 has been deposited on the drill pipe, the neck 18 is stretched to its full length by the downwardly moving holder 25, removing any folds that may have been present 45 when it was disposed on the holder 25.

The spinner holder 26, which has a bore diameter larger than the outside diameter of the flanges 17 when the base is in position upon the 50 drill pipe section, is then passed over the base 12 until the spinner 13 mounted upon it is longitudinally opposite the slot or groove 14, the hydraulic mechanism associated with the holder 26 is operated to deposit the spinner 13 on the base with its end faces 22 opposite the end walls or shoulders 24 of the base and with its bore surface 20 in close proximity to the outer surface 35 of the neck 18. The length of the spinner 13 relative to the groove 14 is such as to provide clearance spaces 28 to allow a small end play between it and the flanges 17 and the diameter of its bore relative to the surface of the neck is such as to provide a clearance space 29 to allow a small radial play between the spinner 60 65 and the neck 18. The outside diameter of the spinner is somewhat greater than the outside diameter of the flanges 17 so that when the protector contacts the side walls or casing of the well, it is the spinner which receives the blow 70 rather than the flanges 17.

While the mud fluid used in the drilling operation may enter clearance spaces 28 and 29 between the spinner and the base, the abrasive solid materials of the mud fluid will not appreciably cut away either the spinner or the base.

because of the resilient character of these bodies. The base tightly fitting upon the drill pipe 27, on the other hand, prevents entrance of any of the mud fluid between the base and the pipe section, thus eliminating any cutting of the walls of the pipe section. The base 12 not only provides an excellent bearing surface upon which the spinner rotates, but by reason of its integrally formed end flanges, retains the spinner longitudinally in place upon the pipe section.

The laminated character of the base gives it a tighter grip upon the pipe, fortifies both the flanges and the neck against laceration and ties the flanges strongly to the innermost laminations of the base which extend through the neck, preventing separation of the flanges from the neck and insuring retention of the spinner in proper position longitudinally of the base.

While the base is preferably formed as hereinabove described, it is apparent that it need not be laminated in structure and that it may even be made of other than rubber or resilient material without losing some of the advantages of this invention. It also need not be a one-piece body, but may be made of two semicircular halves or of other sections suitably secured to form a cylindrical bearing member.

Figs. 9, 10, and 11 illustrate other forms which the invention may take. These forms while not presenting all of the advantageous features of the invention, still have some of the advantages of the invention which are not present in drill pipe protectors as at present known.

In Fig. 9 neck 18a is a separate cylindrical body not integrally or otherwise connected to flanges 17a. A spinner 13a is rotatably mounted upon the neck 18a. While the spinner 13a should be made of rubber or other resilient material, it is apparent that the neck 18a and flanges 17a may be made of other than resilient material, the one requisite being that the neck 18a have a surface contact with the drill pipe 27a to prevent access of the mud fluid to the joint between the neck and drill pipe section.

In Fig. 10 a base 12b is shown as having a central annular ridge 17b which fits within a slot 14b formed on the bore surface of a spinner 13b. The pipe section is protected from cutting action of the mud fluid and the spinner is retained in position longitudinally of the pipe section.

In Fig. 11 a spinner 13c is provided at its ends with insert bearing rings 30 secured to the spinner 13c by bolts 31 or any other suitable means. These bearings may be of steel or a material especially adapted for use in bearings. The bearing rings 30 slidably engage the outer surface of a pipe section 27c preventing access of mud fluid to a clearance chamber 32 between the spinner 13c and pipe 27c and each ring 30 also having an end thrust engagement with a stationary ring 33 of steel or suitable bearing metal disposed on the pipe 27c to prevent endwise movement of the spinner 13c on the drill pipe section 27c. The rings 33 may be split rings arranged for ready securement to the pipe.

It will be apparent from the above description of one embodiment of the invention and of several modifications thereof, that the invention may have many other embodiments. Its essential features are a cylindrical resilient contact element rotatably mounted with respect to the drill pipe, means associated with the mounting for preventing access of the mud fluid

to the surface of the pipe section radially beneath the rotating element, and means for preventing endwise movement of the rotating element on the drill pipe. The invention is not to be limited to any specific embodiment thereof, but is to be given the scope defined by the appended claims.

I claim as my invention:

1. In a drill pipe protector, the combination of: a first hollow cylindrical body of rubber or like resiliently compressible material adapted to be mounted on a drill pipe; a second hollow cylindrical body of rubber or like resiliently compressible material adapted to be concentrically and rotatably mounted on said mounted first body, the bore surface portion of said mounted second body and the peripheral surface portion of said mounted first body being of rubber or like resiliently compressible material and in rotative contact with each other; and means for retaining said second body endwise on said mounted first body.

2. In a drill pipe protector, the combination of: a first hollow cylindrical body of rubber or like resiliently compressible material for stationary mounting on a drill pipe with its bore surface in fluid-tight contact with said pipe; a second hollow cylindrical body of rubber or like resiliently compressible material adapted to be rotatably and concentrically mounted on said mounted first body, the bore surface portion of said mounted second body and the peripheral surface portion of said mounted first body being of rubber or like resiliently compressible material and in rotative contact with each other; and means for retaining said second body endwise on said mounted first body.

3. The combination defined in claim 2 in which said first cylindrical body is formed of one piece of a relatively stretchable material and normally of an inside diameter substantially smaller than the outside diameter of the drill pipe upon which it is to be used and upon which it is thereby adapted to be secured by first expanding it and then shrinking it on said drill pipe, and in which said second body is of substantially harder and less stretchable material than said first body whereby it will better resist abrasion against the sides of a well.

4. In a drill pipe protector, the combination of: a first hollow cylindrical body of rubber or like resiliently compressible material for stationary mounting on a drill pipe with its bore surface in fluid-tight contact with said pipe; and a second hollow cylindrical body of rubber or like resiliently compressible material adapted to be concentrically and rotatably mounted on said mounted first body and secured against longitudinal displacement from said mounted first body, the bore surface portion of said mounted second body and the peripheral surface portion of said mounted first body being of rubber or like resiliently compressible material and in rotative contact with each other, said first cylindrical body being formed of one piece of a relatively stretchable material and normally of an inside diameter substantially smaller than the outside diameter of the drill pipe upon which it is to be used and upon which it is thereby adapted to be secured by first expanding it and then shrinking it on said drill pipe, said second body being of substantially harder and less stretchable material than said first body whereby it will better resist abrasion against the sides of a well.

5. In a drill pipe protector, the combination of: a first hollow cylindrical body of rubber or like

resiliently compressible material adapted to be immovably secured upon a drill pipe in concentric relation thereto; a second hollow cylindrical body of rubber or like resiliently compressible material adapted to be rotatably mounted on said secured first body with an appreciable radial clearance therebetween permitting limited eccentric movement of said second body with respect to said secured first body, the bore surface portion of said mounted second body and the peripheral surface portion of said secured first body being of rubber or like resiliently compressible material and in rotative contact with each other; and means for retaining said second body endwise upon said secured first body while permitting said limited eccentric movement.

6. In a drill pipe protector, the combination of:

a first hollow cylindrical body of rubber or like material adapted to be mounted on a drill pipe; a second hollow cylindrical body of rubber or like material adapted to be concentrically and rotatably mounted on said mounted first body with an appreciable radial clearance therebetween permitting limited eccentric movement of said second body on said first body, the bore surface portion of said mounted second body and the peripheral surface portion of said mounted first body being of rubber or like resiliently compressible material and in rotative contact with each other; and means for retaining said mounted second body endwise on said mounted first body, said means being adapted to permit limited endwise play of said second body.

WALTER G. L. SMITH.
